(57) **CLAIM**

The ornamental design for an appliance door handle, as
shown and described.

DESCRIPTION

FIG. 1 is a front perspective view of an appliance door
handle according to our design;

FIG. 2 is a front perspective detail view of area 2 indicated
in FIG. 1;

FIG. 3 is a front elevation view of the appliance door handle
of FIG. 1;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The appliance door handle is shown with a symbolic break
in its length. The appearance of any portion of the article
between the break lines forms no part of the claimed design.
